UNITED STATES PATENT OFFICE.

IRA T. SWARTZ AND ALVIE T. WALLACE, OF INDIANAPOLIS, INDIANA, ASSIGNORS TO SWARTZ ELECTRIC COMPANY, OF INDIANAPOLIS, INDIANA, A CORPORATION OF INDIANA.

TIMER FOR INTERNAL-COMBUSTION ENGINES.

1,293,574.

Specification of Letters Patent.

Patented Feb. 4, 1919.

Application filed October 22, 1917. Serial No. 197,948.

To all whom it may concern:

Be it known that we, IRA T. SWARTZ, a citizen of the United States, residing at Indianapolis, Marion county, and State of Indiana, and ALVIE T. WALLACE, a citizen of the United States, residing at Indianapolis, Marion county, and State of Indiana, have invented and discovered certain new and useful Improvements in Timers for Internal-
10 Combustion Engines, of which the following is a specification.

Our invention relates to timers for internal combustion engines and particularly to timers for engines having a constant speed, such as those for driving a generator forming part of an individual electric power plant, and the objects of the invention are to provide means whereby the timer may be fixed at the best predetermined position
20 and held against intentional or accidental change of position except within a predetermined limited range of movement, and whereby the timer is so mounted in association with the units of the generator set such as the internal combustion engine and the motor-generator as to be readily accessible for assemblage and removal or adjustment.

With these objects in view, our invention is embodied in preferable form in the construction and arrangement hereinafter described and illustrated in the accompanying drawings.

In these drawings, Figure 1, is a side view in elevation, partly in section, of a generator set, with our invention applied thereto; Fig. 2, an enlarged detail vertical section on the line 2-2 of Fig. 1 and Fig. 3, an enlarged detail side view of the timer.

Referring to the drawings, 1 is a stationary internal combustion engine adapted to run at constant speed, 2 is a motor-generator mounted on the shaft of the said engine and 3 is a fly wheel at the end of the shaft. This fly wheel carries fixed thereon an annular
45 wiper cam 4 against which bears a spring contact member 5 adapted to be intermittently operated by the cam and to open and

close the circuits through the contact carried by the set screw. This set screw 6 is carried by a projecting arm 7 extending from an adjustable timer plate 8 consisting of a split ring surrounding a hub 9 and having its ends connected by a clamping bolt 10 whereby the timer is fixed to the hub and may be adjusted circumferentially thereof. The hub 9 extends from a disk 10' which is secured by screws 11 to an enlarged, fixed boss 12 preferably formed integral with the bracket of the generator and surrounding the shaft of the latter.

This provision of the housing for the timer contacts on the generator bracket at the outer end of the latter in conjunction with the mounting of the wiper cam within the fly wheel affords a construction in which the timer is readily accessible for adjustment, insertion and removal.

Formed in the periphery of the timer member 8 is an elongated circumferential slot 13 within which projects axially a stop screw 14 mounted in the plate 10' carried by the fixed boss 12. This slot 13 is of a predetermined length and measures a range of movement for the timer within which the same may be adjusted to produce the most effective timing action of the constant speed engine, and the slot and pin 14 are initially set at the time of the assemblage of parts at the correct timing position. This arrangement prevents the timer from being accidentally displaced during shipment or when being set up, and yet permits a sufficient adjustment after the generator has been tested to obtain the desired timing action.

The timer is connected to any suitable electrical sparking mechanism.

Having thus described our invention, what we claim is:—

In combination with an internal combustion engine and a motor-generator, a common shaft for said engine and generator, a fly wheel at the outer end of the shaft, a rotatable timer element carried by said fly

wheel, a generator bracket adjacent said fly wheel, a boss carried by said bracket and surrounding said shaft, and a removable and circumferentially adjustable and relatively fixed timer element carried by said boss adjacent to said fly wheel.

In witness whereof, we have hereunto set our hands and seals at Indianapolis this

8th day of October, A. D. nineteen hundred and seventeen.

IRA T. SWARTZ. [I. S.]
ALVIE T. WALLACE. [L. S.]

Witnesses:

O. W. LESTER,
CLARA SCHROEDER.
